FOOT BATH

Milton H. Martindell and Oscar Stenmar, Trenton, N. J., assignors to Jos. Stokes Rubber Co., Trenton, N. J., a corporation of New Jersey

Application November 3, 1932, Serial No. 641,080

2 Claims. (Cl. 4—182)

This invention relates to improvements in receptacles for use in treatment of foot afflictions. These receptacles commonly take the form of a shallow tray in which is placed a solution of a germicide or medicament suitable for the purpose.

The principal object of our invention is to provide a receptacle of the stated character which shall constitute a general improvement over prior devices of like character.

Another and more specific object of the invention is to provide a receptacle which shall be relatively sanitary.

Still another object of the invention is to provide a receptacle of the stated character which while being relatively light in weight shall possess the high degree of strength required by the conditions under which the receptacle is used.

A still further object of the invention is to provide a receptacle of the general character set forth above which shall possess the necessary stability coupled with ability to maintain itself in any given position upon the floor surface.

In the attached drawings:

Figure 1 is a view in perspective of a foot bath receptacle made in accordance with our invention;

Fig. 2 is a section on the line 2—2, Fig. 1;

Fig. 3 is an inverted plan view of the receptacle; and

Fig. 4 is an enlarged fragmentary sectional view showing a detail of the invention.

Referring to the drawings, the receptacle consists of a relatively shallow tray of generally rectangular form in the present instance, said tray comprising a bottom member 1 terminating in substantially vertical side walls 2. From the upper edges of the walls 2 a continuous flange 3 extends outwardly and downwardly at an inclination of approximately 45° from the plane of the bottom 1, and this flange preferably terminates at its lower edge, as shown in Figs. 2 and 4, on a line slightly elevated above the under surface 4 of the bottom member 1. As shown in Figs. 2, 3 and 4, the outer surfaces of the side walls 2 and the inner surfaces of the flange 3 are connected at spaced points completely around the tray by means of a series of webs 5, the lower edges 6 of these webs terminating as shown in Figs. 2 and 4 at points above the lower edge of the flange 3. Preferably the outer or exposed surface of the inclined flange 3 is provided with markings or is otherwise roughened for a purpose hereinafter set forth.

In accordance with our invention, we form our

tray of hard vulcanized rubber, this providing the hard close-grained surface required to maintain the tray in sanitary condition, and also having for a given weight the relatively great strength required in an article subjected to the 60 conditions under which receptacles of this character are used. Hard rubber, however, has slight frictional characteristics, and in order to prevent the tray from sliding upon the floor surface, we form the under portion of the bottom wall 1 of 65 flexible rubber. This flexible base preferably is formed as an integral part of the tray, although obviously it may be constituted by a flexible rubber sheet attached to the under side of the tray bottom by any suitable means. This soft rubber 70 base not only prevents slipping of the tray from its desired position upon the floor, but also acts as a cushion relieving strain upon the bottom of the tray resulting from the successive applications of weight and producing generally improved 75 characteristics for the tray as a whole.

The flanges 3 extending away from the upper edges of the walls 2 give the tray the necessary stability on the floor and preclude the possibility of the tray being tilted by the weight of the body 80 coming upon the upper edge of the side walls 2. In order to reduce the possibility of the foot slipping on the inclined surface of the flange 3, we preferably form this surface with indentations or irregularities as previously set forth affording 85 in effect non-skid characteristics. These flanges 3 are fully reinforced and the side walls 2 given all the strength required to withstand the strains of normal use by the reinforcing webs 5, which give the walls as a whole including the flanges 3 90 substantial rigidity. These flanges while affording all the necessary strength do not materially increase the weight of the tray as a whole. It will be noted that the lower edges of the flange 3 terminating above the plane of the lower surface 95 of the bottom 1 of the tray insures the soft rubber at the latter surface bearing throughout upon the floor surface and being effective in its intended function. Slight pressure upon the tray, however, brings the lower edges of the flanges 3 into contact with the floor surface by compression of the soft rubber portions 4, so that complete stability is 100 achieved.

Heretofore it has been proposed to make trays of this character of soft rubber throughout. 105 These trays, however, have not proved satisfactory by reason among others of the soft rubber being relatively hard to maintain in sanitary condition, the surfaces being relatively porous as compared with the hard vulcanized rubber employed in our 110

bath. These soft rubber trays also are more liable to destruction and have not got the physical strength of the hard rubber product. Also their weight for a given size is relatively great; and 5 since the edges of the trays are flexible, there is also considerable danger of spillage of the contents by distortion of the edges when weight is accidentally placed thereupon.

A tray made in accordance with my invention 10 has all the advantages and none of the disadvantages of the prior commercial product. It is strong, durable, stable and practically fool-proof. It may be readily maintained in sanitary condition and in all respects meets the requirements 15 of purpose for which intended.

We claim:

1. A receptacle of the character set forth comprising a tray of hard vulcanized rubber comprising a bottom member having an upper hard and relatively compact surface and an under flexible 20

surface, said bottom terminating in substantially vertical walls of hard rubber, and a flange extending from the upper edge of said side walls outwardly and downwardly and terminating short of the plane of the under flexible surface of the 80 bottom member.

2. A receptacle of the character set forth comprising a tray of hard vulcanized rubber comprising a bottom member having an upper hard and relatively compact surface and an under flexible 85 surface, said bottom terminating in substantially vertical walls of hard rubber, a flange extending from the upper edge of said side walls outwardly and downwardly and terminating short of the plane of the under flexible surface of the bottom 90 member, and reinforcing webs extending between the outer surfaces of the said walls and the inner surfaces of the flange.

MILTON H. MARTINDELL.
OSCAR STENMAR.
